UNITED STATES PATENT OFFICE.

JOHN N. HUSHER, OF MONESSEN, PENNSYLVANIA.

VALVE-CONTROLLING MECHANISM.

1,326,402.

Specification of Letters Patent. Patented Dec. 30, 1919.

Application filed January 12, 1915, Serial No. 1,863. Renewed May 28, 1919. Serial No. 300,479.

To all whom it may concern:

Be it known that I, JOHN N. HUSHER, a citizen of the United States, and resident of Monessen, in the county of Westmoreland and State of Pennsylvania, have invented a new and useful Improvement in Valve-Controlling Mechanism; and I do hereby declare the following to be a full, clear, and exact description thereof.

10 My invention relates to valve controlling mechanism adapted more particularly for use in connection with a condenser such as illustrated and described in a patent granted to me February 2, 1915, No. 1,127,252, in 15 which there is a thermostatic arrangement for closing the valve leading from the water-supply to the condenser.

The object of my invention is to provide an efficient and simple controlling device 20 whereby an ordinary butterfly-valve in the water-supply pipe may be automatically controlled to furnish the proper amount of water to the condenser according to the supply of exhaust steam admitted to the 25 condenser.

In the accompanying drawings, Figure 1 is a vertical sectional view of a condenser showing my invention applied thereto, the valve controlling device not being shown in 30 section; and Fig. 2 is an enlarged view of the valve mechanism partly in section.

In the drawings, Fig. 1 embodies the condenser, which forms the subject matter of a separate application above referred to. 35 The numeral 2 designates a suitable casing mounted on a standard or support 3. A steam-pipe 4 leading from the exhaust of the engine communicates with the casing 2 for the admission of steam thereto. An injector-pipe 5 leading from a suitable water-supply enters the casing 2 at the upper end thereof. Within the casing 2 is the rod 6, which is fixed as at 7 at its lower end, and the upper end of said rod is connected to 40 the lever 8 fulcrumed at 9 on the support 10 outside of said casing 2. A rod 11 is connected to the opposite end of the lever 8, said rod extending down into the casing and connected at its lower end to the lever 12, fulcrumed at 13. A rod 14 is connected to the opposite end of the lever 12, said rod extending up through the casing and connected at its upper end to the lever 15, fulcrumed at 16. A rod 17 is connected to the opposite 55 end of the lever 15, and said rod is connected at its lower end to the arm 18 of an ordinary

nary valve 19. This valve 19 is located in the pipe 20, which at its lower end is connected to the injector-pipe 5, and at its upper end to the port 21 leading to the lower 60 end of the cylinder 22.

The cylinder 22 is surrounded with the water-jacket 24, and a pipe 25 connects said water-jacket with the pipe 5.

Within the cylinder 22 is the piston 26. A 65 piston-rod 27 is connected with the piston 26. A cross-head 28 at the lower end of said piston-rod engages the guides 29 in the skirt 30, which is secured to the pipe 5 by means of the U-shaped bolts 31. 70

A link 32 connected with the piston-rod 27 is connected at its lower end to the arm 33, said arm being connected to the ordinary butterfly-valve 34 in the pipe 5. A weight 35 is connected to the outer end of the 75 arm 33.

A series of spirally arranged openings 36 are provided in the cylinder 22, said openings forming communication between said cylinder and the water-jacket 24, and said 80 openings are controlled by needle-valves 37 engaging openings 38 arranged to correspond with the openings 36. In this manner, the size of the openings 36 may be accurately controlled. 85

When the exhaust-steam from the engine is passing through the pipe 4 into the condenser, the butterfly-valve 34 will be open to permit the water to pass by the pipe into the condenser. The water by its cooling action condenses the steam in the ordinary manner of jet-condensers; but if the load on the engine is reduced, the fixed rod 6 cools accordingly, and as said rod is held in fixed position at its lower end, the contraction of 90 said rod will pull down on one end of the lever 8, and will, thereby, lift the rod 11. This will act through the lever 12 to lower the rod 14, and through the lever 15, raise the rod 17. The arm 18 of the valve will be 100 operated to admit water by the pipe 20 through the port 21 into the lower end of the cylinder 22. This will act to elevate the piston 26, and as said piston ascends, the link 32 will raise the arm 33, and the butterfly-valve 34 will be moved toward closed position. The amount of upward movement of the piston 26 and accordingly of the valve 34, will depend upon the size of the openings 36 and the amount of water that is 110 allowed to escape through said openings; and the height to which the piston 26

ascends is controlled by the combined area of the openings 36, which are passed by the piston in its ascent. When the piston has ascended to a point where the combined area 5 of the openings 36 passed by said piston is equal to the area of the pipe 20, the piston will be balanced and the water will flow through the openings uncovered by the piston into the water-jacket 24, whence it passes 10 by the pipe 25 into the pipe 5. As long as the supply of exhaust-steam is such as to cause the contraction of the rod 6 in the manner above described, the piston 26 will remain in this position and the valve 34 will 15 be in position to admit the proper amount of water to the condenser. If, however, the steam should be entirely cut off, the piston 26 would rise to a higher point and so completely close the valve 34 and cut off the 20 water supply to the condenser.

When the engine is again put in operation and the exhaust-steam is admitted to the condenser, the rod 6, instead of contracting, will expand, and through the connections 25 described, this will close the valve 19 and the weight 35 will act to lower the piston 26 and open the butterfly valve 34. The device is thus very sensitive and accurate in its control of the valve 34 so that when once 30 the size of the openings 36 has been determined to correspond to the amount of expansion and contraction which takes place in the rod 6, the supply of water to the condenser is controlled with great accuracy; 35 and when once the proper adjustments have been made, the device works automatically and without further attention.

By my invention, I am able to employ an ordinary butterfly-valve, which is one of the 40 simplest forms of valve and liable to the least amount of wear, and, consequently, from an economical standpoint, effects a great saving.

What I claim is:

45 1. The combination with a condenser having steam and water-inlets and a thermostatic device, of a butterfly-valve controlling the water-inlet, a cylinder having spirally arranged openings, a piston in said cylinder moving over said openings, and whose ascent is controlled by the combined area of 50 said openings passed by said piston, connections between said piston and said butterfly-valve, a pipe-system for supplying fluid

to the lower end of said piston, a valve in said pipe-system, and connections between said last-named valve and said thermostatic device.

2. The combination with a condenser having steam and water-inlets and a thermostatic device, of a butterfly-valve controlling the water-inlet, a cylinder having spirally arranged openings, a piston in said cylinder moving over said openings, and whose ascent is controlled by the combined area of said openings passed by said piston, connections between said piston and said butterfly-valve, a pipe system for supplying liquid to the lower end of said piston, a valve in said pipe-system, and connections between said valve and said thermostatic device. 60 65 70

3. The combination with a condenser having steam and water inlets and a thermostatic device, of a butterfly-valve controlling the water inlet, a cylinder having spirally arranged openings, a piston in said cylinder moving over said openings, and whose ascent is controlled by the combined area of said 75 80 85 openings passed by said piston, connections between said piston and said butterfly-valve, a pipe communicating with the water inlet below said butterfly-valve and communicating with the lower end of said cylinder, a valve controlling said pipe, and connections between said valve and said thermostatic device.

4. The combination with a condenser having steam and water inlets and a thermostatic device, of a butterfly-valve controlling the water-inlet, a cylinder having spirally arranged openings, a piston in said cylinder moving over said openings, and whose ascent is controlled by the combined area of 90 95 said openings passed by said piston, connections between said piston and said butterfly-valve, a pipe for supplying fluid to the lower end of said piston, a valve in said pipe, connections between said last-named valve 100 and said thermostatic device, and a weight connected to said piston.

In testimony whereof I the said JOHN N. HUSHER have hereunto set my hand.

JOHN N. HUSHER.
